US00D782301S

(12) United States Design Patent (10) Patent No.: US D782,301 S
(45) Date of Patent: * Mar. 28, 2017

(54) PACKAGE WITH SURFACE
ORNAMENTATION

(71) Applicant: PHILIP MORRIS PRODUCTS S.A.,
Neuchâtel (CH)

(72) Inventors: Rory McGarry, Dublin (IE); Jeffrey
Simons, The Hague (NL)

(73) Assignee: PHILIP MORRIS PRODUCTS S.A.,
(CH)

() Term: 14 Years

(21) Appl. No.: 29/512,173

(22) Filed: Dec. 17, 2014

(30) Foreign Application Priority Data

Jun. 25, 2014 (EM) 002490516-0002

(51) LOC (10) Cl. 09-03

(52) U.S. Cl.

USPC D9/434; D5/63

(57) CLAIM

The ornamental design for a package with surface ornamentation, as shown and described.

DESCRIPTION

The sole drawing FIGURE is a front view of a package with surface ornamentation.

The broken lines surrounding the drawing depict a package that forms no part of the claimed design.

1 Claim, 1 Drawing Sheet
